UNITED STATES PATENT OFFICE.

THOMAS J. LITTLE, JR., OF DETROIT, MICHIGAN, ASSIGNOR TO COPELAND PRODUCTS, INC., OF DETROIT, MICHIGAN, A CORPORATION OF MICHIGAN.

PUMPING MECHANISM.

Application filed September 18, 1926. Serial No. 136,357.

The object of my invention is to provide a motor in connection with a refrigerating system which may be used to operate various culinary and household appliances independently of the operation of the refrigerant circulatory system.

A further object of my invention is to provide means for rendering the refrigerant circulatory system inoperative when it is desired to use the motor to operate various culinary and household appliances.

With these and other objects in view, my invention consists in the arrangement, combination and construction of the various parts of my improved device, as described in the specification, claimed in my claims and shown in the accompanying drawings, in which:

Fig. 1 is a side elevation of a refrigerator cabinet with parts broken away and having a refrigerating system embodying my invention attached thereto.

Fig. 2 is a sectional view of the compressor of a refrigerating system embodying my invention.

Fig. 3 is a diagrammatic sketch of the electrical connection between the motor of said refrigerating system, and my invention.

I have shown a refrigerator cabinet 1 having a motor 6 with a refrigerant compressor 7 secured thereto, mounted on the cabinet top 2. Within the upper portion of the cabinet 1 is positioned a refrigerant expansion chamber 8, and on the exterior back wall of cabinet 1 is positioned a refrigerant condenser 9. The pipe 10 connects the compressor 7 with the condenser 9; the pipe 11, the expansion valve 12 and the pipe 13 connect the condenser 9 with the expansion chamber 8, and the pipe 14 connects the expansion chamber 8 with the compressor 7, thus completing the refrigerant circulatory system.

The shaft 15 of the motor 6 has its end 16 fashioned for operative engagement with sundry culinary and household appliances such as egg beaters, etc., and the motor 6 is so positioned upon the cabinet top 2 as to permit the shaft 15 to extend over an unoccupied portion of the cabinet top 2 upon

which may be positioned as desired the various culinary and household appliances which are operable by the shaft 15.

The compressor 7 which is secured to the motor 6 comprises a housing 20, a cylinder 21 formed integrally with the upper portion of the housing 20, and a hollow piston 22 operable in cylinder 21. Within the piston 22 and bearing at one end against the closed end 23 of the piston 22 and at the other end against the head 24 of cylinder 21 is a coil spring 25 normally tensioned to force the piston 22 downward for its downward stroke through cylinder 21. The shaft 15 of the motor 6 extends into the lower portion of housing 20 beneath the closed end 23 of piston 22, and has an eccentric or cam 26 secured to the end thereof for operative contact with the closed end 23 of piston 22. The cam 26 rotates with the shaft 15 and by its contact with the closed end 23 of piston 22 forces piston 22 upward through cylinder 21 at spaced intervals, and thus causes the upward stroke of the piston.

Formed on the upper part of the housing 20, and integral therewith, is a valve housing 27 having an inverted and reversed L shaped chamber 30, the vertical end of which leads into the top of cylinder 21. Beneath the horizontal portion of the chamber 30, in the valve housing 27, is formed a reversed L shaped passage 31 the horizontal end of which is adapted to receive the end of intake pipe 14, and the vertical end of which opens into the horizontal portion of chamber 30. The vertical end of passage 31 is enlarged and recessed where it opens into chamber 30 to form the flange 32 around the end of passage 31 for supporting the movable valve plate 33 which covers the end of passage 31 and completes the intake valve for the compressor 7.

An internally screw-threaded opening 34 leading into the horizontal portion of chamber 30 directly above the vertical end of intake passage 31, is provided in the top of housing 27.

An electro-magnet 40 having a winding 41 and a core 42 extended beyond the winding 41, is secured in the opening 34 with the end 100

of core 42 extended within the horizontal portion of chamber 30 to a point removed from and directly above the valve plate 33. The magnet 40 is tightly secured in the opening 34 by the screw plug 43 which is secured around core 42 below the winding 41 and which has a flange 44 formed on its upper portion for overlapping the edges of opening 34, and external screw threads on its lower portion adapted to fit the threads of opening 34. The wires 45 and 46 extend to the source of electric current (not shown) and the motor 6 respectively, thus connecting the electro-magnet 40 in series with the motor 6.

In Fig. 3 I have shown a diagram of the electrical wiring in which the electrical current is carried from its source through wire 45 to magnet 40, and from magnet 40 by wire 46 to switch terminal 47. Between the source of current and the magnet 40 the wire 45 is tapped by the wire 60 which carries current to a control device 61 which consists of a tiltable bulb having mercury therein, adapted when the bulb is tilted to make or break the circuit to control the operation of the motor 6. Various thermostatically operated devices for actuating the bulb in response to the temperatures within the cabinet 1 may be used, one of which is the subject matter of my application for Letters Patent of the United States on control for refrigerating mechanism, filed June 12, 1926, Serial No. 115,686. The wire 62 connects the control device 61 with the switch terminal 49. The wire 50 leads from the switch terminal 48 to the motor 6 and the wire 52 leads from the motor 6 to ground, thus establishing a circuit through the motor 6 whenever points 48 and 49 or 47 are connected. Any suitable switch may be used to connect terminals 48 and 49 or 47 to obtain a circuit through motor 6 and either the thermostatic control 61 or the magnet 40.

In operation, the motor 6 when supplied with current causes the operation of piston 22 in cylinder 21 of the compressor 7. Normally the downward stroke of piston 22 will cause the valve closure 33 to be lifted from flange 32 at the end of passage 31 and will draw refrigerant from the expansion chamber 8 through pipe 14, passage 31 and chamber 30 into cylinder 21. The upward stroke of the piston 22 will compress the refrigerant, force the valve closure 33 down against flange 32 and thus close the passage 31, and the compressed refrigerant will be forced out of cylinder 21 through a suitable outlet valve (not shown) into pipe 10 and so to the condenser 9, thus causing a circulation of refrigerant.

When it is desired to have the motor operate any of the various culinary and household appliances which may be attached to

the end 16 of the shaft 15 without causing a circulation of refrigerant, the motor may be switched out of connection with the thermostatic control 61, thus causing the electric current to pass through the winding 41 of the magnet 40 and energize the core 42 which will attract the metal valve plate 33, lift it from its seat on flange 32 and retain it against the end of core 42 so long as current is passing through winding 41. The passage 31 is thus held open and the operation of the piston 22 in the cylinder 21 will merely move refrigerant back and forth through passage 31 and pipe 14 to the expansion chamber 8 without compressing it or forcing it into the condenser 9, consequently the refrigerant is not circulated through the system and no refrigeration takes place within the cabinet while the motor is being operated with the compressor intake valve open.

It will be obvious that various changes may be made in the arrangement, combination and construction of the various parts of my improved device without departing from the spirit of my invention, and it is my intention to cover by my claims such changes as may be reasonably included within the scope thereof.

What I claim is:

1. In combination, an electric motor, a pump connected thereto for continuous simultaneous movement therewith, said pump being provided with a pumping chamber and an inlet passage leading thereto, a seat in said passage, a valve member co-operating with said seat for limiting the flow of fluid through said passage to one direction only, an electro-magnet, a fixed core for said magnet extending through a wall of said passage into spaced relationship in respect to said valve member on the side thereof opposite to said seat for limiting the lifting movement of said valve member from said seat, and means for energizing said electro-magnet whereby to hold said valve member away from said seat.

2. In combination with a pump having a pumping chamber and an inlet passage leading thereto, a valve seat in said passage, a valve co-operating with said seat permitting flow of fluid through said passage in one direction only, an electro-magnet, and a fixed core for said magnet projecting through a wall of said passage and terminating on the opposite side of said valve from said seat and in spaced relationship in respect thereto for lifting said valve and limiting the lifting movement of said valve during the normal functioning of said pump.

3. In combination, a pump having a pumping chamber and an inlet passage leading thereto, a valve seat in said passage, a valve member co-operating with said seat, and an electro-magnet comprising a core and

winding, said core extending through the said valve during normal operation of said walls of said passage and terminating in pump, and acting to hold said valve away normally spaced relationship with respect to from said seat when said magnet is energized, whereby said pump may be operated 10
said valve member on the side thereof opposite to said seat, and said windings being positioned exteriorly of said passage, said core providing a stop for limiting the lift of
